UNITED STATES PATENT OFFICE.

JEROME J. RODENBERG, OF PROVIDENCE, RHODE ISLAND, ASSIGNOR TO THE M. S. RODENBERG CO., OF PROVIDENCE, RHODE ISLAND, A CORPORATION OF RHODE ISLAND.

VANITY CASE.

Application filed February 5, 1925. Serial No. 7,144.

To all whom it may concern:

Be it known that I, JEROME J. RODENBERG, a citizen of the United States, residing at Providence, in the county of Providence and State of Rhode Island, have invented certain new and useful Improvements in Vanity Cases, of which the following is a specification.

This invention relates to a construction 10 of case or receptacle which is employed more particularly for carrying toilet preparations such as powder and rouge; and the invention has for its object to provide an improved construction of such a receptacle 15 or casing having a body portion and a lid hinged thereto, each adapted to carry a cake 20 of powder, rouge or other toilet preparation, and a mirror so mounted on either the body or lid that it may be swung into position to be used, while both the rouge and the powder 25 are being applied.

A further object of this invention is to provide a mirror which will automatically swing from its folded position in the casing 30 to its extended position upon the lid member of the casing being moved to open position, the said mirror being so mounted that upon its being swung to extended position the rouge and powder compacts will be both simultaneously fully exposed for use.

With these and other objects in view, the invention consists of certain novel features of construction, as will be more fully described, and particularly pointed out in the 35 appended claims.

In the accompanying drawings:

Figure 1 is a perspective view of my vanity case in closed position.

Figure 2 is a plan view showing my powder case in open position with its mirror pivotally mounted on the lid and swung to extended position.

Figure 3 is a side elevation of the same.

Figure 4 is a sectional elevation of my mirror carrying member showing the pivot pin as cut and bent down into operative position from the bottom of said member.

Figure 5 is a sectional elevation of my lid member and mirror mounted thereon, on substantially line 5—5 of Figure 2.

Figure 6 is a fragmental sectional elevation of the same taken substantially on line 6—6 of Figure 2.

Figure 7 is a partial sectional elevation

taken substantially on line 7—7 of Figure 55 1 but showing only my casing in section.

It is found in the practical construction of a powder and rouge carrying case, of advantage to so mount the mirror carried in such a case that it may be automatically 60 swung to a position to be used for the application of either the powder or rouge carried in the case, without the necessity of changing or manipulating the mirror or the case for the more advantageous application 65 of either of these two toilet preparations; and the following is a detailed description of the present embodiment of my invention showing one construction by which these 70 advantageous results may be accomplished:

With reference to the drawings, 10 designates the body member of the casing, which is preferably of a diameter to receive the standard size cake of powder 11 and powder-puff 12. Hinged to the body as at 34 75 is a lid member 13 in which is a deck plate 14 having a recess or opening 15 therein for the reception of a cake of rouge 16.

A mirror-mounting member 17 having a 80 mirror 18 secured therein is pivotally mounted as at 19 on the said deck plate to swing in a plane substantially parallel to this plate from its folded position, as shown in Figure 7, to its extended position, as shown in Figure 2. I pivotally mount the mirror 85 carrying member 17 upon the deck plate 14 by means of a pivot pin 20 which may be formed in any desired manner but as here shown is formed by cutting and bending down a portion of the stock in the bottom 90 of the member 17. This finger 20 is passed through an opening 21 in the deck plate 14 and a sleeve 22 flanged as at 24 to provide an increased bearing surface, is fixedly 95 mounted on this pin 20 by any suitable means such as solder 23.

In order that the mirror will automatically assume its extended position, as shown in Figure 2, a spring 25 is coiled about the sleeve 22, one end of the same being 100 fixed to the sleeve by passing it through an opening 26 therein and the other end being fixed to a finger 27 cut and bent downwardly from the stock of the deck plate 14.

Upon closing this powder case, the operator manually folds the mirror 18 into the casing by swinging the same on its pivot to cover the rouge recess 15 and then the lid 105

is moved to closed position and retained in this position by means of a catch 28. The walls of the casing hold the mirror in this folded position by engagement of the mirror with the edge walls 29, as illustrated in Figure 7. In opening the casing, the catch 28 is operated by a presser member 30 to release the lid and upon moving the lid to open position, as shown in Figures 2 and 3, the spring 25 being under tension automatically moves the mirror from its folded position to its extended position against the limiting stop 31.

It will be understood that by swinging my mirror to its folded position, the spring is placed under tension and that upon the opening of the case the spring under its maximum tension initially starts the moving of the mirror to swing it to its extended position against the stop, the maximum tension of the spring being utilized to overcome the inertia of the mirror.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A vanity case comprising two toilet preparation receiving receptacle members hinged together, a mirror pivotally mounted

ed on one of said members to swing in a plane parallel to the plane of the member to which it is attached, means for automatically moving said mirror to extended position upon the swinging part of said hinged members, and a stop to limit the swinging movement of said mirror.

2. A vanity case comprising body and lid members, a deck plate in one of said members, a mirror supported by and pivotally mounted on said plate to slide thereover, spring means for sliding said mirror over said plate to open position upon the moving of said lid to open position, said mirror being manually foldable within said casing to be held in folded position by the edge wall of the lid when closed.

3. In a vanity case, body and lid members, a mirror carrying plate having a portion of its stock cut and bent down to form a pivot pin, said pin being pivotally mounted in one of said members.

4. In a vanity case, body and lid members, a mirror carrying plate having a portion of its stock cut and bent down to form a pivot pin, said pin being pivotally mounted in one of said members, and a spring acting on said pin to move said plate laterally relatively to said members.

In testimony whereof I affix my signature.

JEROME J. RODENBERG.
